United States Patent Office

Des. 185,699
Patented July 21, 1959

185,699

ELECTROMAGNETIC RELAY

Walter F. Dowdle, Lincoln, Ill., assignor to Essex Wire
Corporation, Fort Wayne, Ind.

Application July 22, 1957, Serial No. 47,046

Term of patent 14 years

(Cl. D26—13)

Des. 185,699

PAGE 2

Figure 1 is a perspective view of an electromagnetic relay, showing my new design;

Figure 2 is a top plan view;

Figure 3 is a side elevational view, the opposite side being substantially a mirror image thereof;

Figure 4 is a bottom plan view;

Figure 5 is a front elevational view; and

Figure 6 is a rear elevational view thereof.

The dominant features of my new design are shown in solid lines in the drawing.

I claim:

The ornamental design for an electromagnetic relay, as shown and described.
